LIPSTICK HOLDER

Donald L. Spender, Naugatuck, Conn., assignor
to Scovill Manufacturing Company, Waterbury,
Conn., a corporation of Connecticut

Application November 20, 1947, Serial No. 787,161

9 Claims. (Cl. 206—56)

1

This invention relates to lipstick holders of what might be termed the push-up type, wherein the lipstick is extended and retracted with respect to the casing of the holder by upward and downward sliding movement of the cartridge. Still more particularly, the invention relates to devices of the character described, wherein the cartridge is so mounted and constructed as to adapt it for use in conjunction with a longer lipstick and, wherein, the casing opening is maintained closed at all times as the cartridge and its associated sleeve are movable longitudinally of the casing.

The novel features of the invention will be best understood from the following description, when taken together with the accompanying drawing, in which certain embodiments of the invention are disclosed and, in which, the separate parts are designated by suitable reference characters in each of the views and, in which:

Fig. 1 is an exploded view showing a side elevation of a holder made according to my invention with the cover detached with respect to the holder and showing the lipstick extended.

Fig. 2 is an enlarged sectional view through the holder with the lipstick in a partially extended position, the cartridge being shown in elevation.

Fig. 3 is a view similar to Fig. 2 showing parts in a different position and with the cartridge in section.

Fig. 4 is an enlarged cross-section on the line 4—4 of Fig. 3.

Fig. 5 is a perspective view of the sleeve which I employ detached.

Fig. 6 is a side view of a modified form of sleeve which I employ; and

Fig. 7 is a section on the line 7—7 of Fig. 6.

In practice, my improved holder comprises three primary parts, namely a casing 10, a sleeve 11 and a cartridge 12. The casing 10 is of one diameter throughout the major portion of its length and has, at its lower end, a circumferentially grooved enlarged portion 13 adapted to receive a closure plate or cap 14 having circumferentially spaced outwardly beaded spring fingers 14', note Fig. 3. The fingers 14 are adapted to extend into the grooved portion 13 and have a spring engagement therewith, as will clearly appear in said figure. The upper end of the casing 10 has an inturned annular flange 15 forming an opening 16, through which the lipstick 17 mounted in the cartridge 12 is adapted to freely pass.

The wall of the casing, at the upper portion

thereof, has an inwardly pressed nib 18 which is elongated longitudinally with respect to the casing and the lower portion of the casing has an outwardly extending nib 19, providing for frictional mounting of a closure cap or thimble 20 with the casing, the cap seating upon the enlargement 13 or the shoulder portion 21 formed thereby.

The sleeve 11 is in the form of what is termed a split sleeve and, from this standpoint, can be readily formed from a flat sheet or strip of material. The sleeve has an elongated opening 22 in the wall thereof opposed to the split 23, the opening 22 registering with an elongated opening 24 in the casing 10. The split of the sleeve 11 is enlarged for approximately one-half of the sleeve length to form a keyway 25, which registers with the nib 18 and, in which, the nib operates in guiding the sleeve longitudinally of the casing, while preventing rotation of the sleeve therein. The aperture 22 in the sleeve is substantially one-half the length of the aperture 24 in the casing, thus when the parts are in their lowermost position, the aperture 22 is at the lower portion of the aperture 24, whereas in extending the lipstick 17 in the manner seen in Figs. 1 and 3, the aperture 22 extends to the upper portion of the aperture 24 and the sleeve 11, as well as the cartridge 12, are at their limit of upward travel.

The sleeve 11 has, at its upper and lower ends, inturned stop members, 26 and 27 which limit movement of the cartridge 12 in both directions in the sleeve. In other words, assuming the parts to be in the position shown in Fig. 2, upward sliding movement of the cartridge will cause the upper end of the cartridge to strike the members 26 to move the sleeve upwardly to the position shown in Fig. 3; whereas in the downward movement, the cartridge strikes the members 27 to, in like manner, return the sleeve to the position shown in Fig. 2.

The cartridge 12 has a series of circumferential ribs 28 spaced longitudinally of the periphery thereof forming gripper surfaces disposed through the opening 22 to facilitate sliding movement of the cartridge longitudinally of the casing. The cartridge has upper and lower bores 29 and 30, the upper bore forming the chamber for reception of the lipstick 17. The two bores are separated by a partition wall 31, which has an upstanding bevelled and apertured center member 32 engaging the lipstick to aid in retaining the lipstick against displacement from the bore or socket 29. The member 32 has a spread-

ing action upon the lipstick to insure firm engagement with the walls of the bore 29.

It is also preferred that the sleeve 11 be slightly out-of-round so as to establish frictional engagement with the walls of the casing and this is indicated in Fig. 4 of the drawing. In other words, a slight binding action or frictional engagement is provided between the side of the casing having the nib 18 and the side of the casing having the aperture 24. The sleeve 11 also has frictional engagement with the cartridge sufficient to maintain the cartridge against free movement in the sleeve. It will also be apparent that the split in the sleeve 11 facilitates expansion of the sleeve to pass the stop members or lugs 26, 27 over the cartridge in assemblage.

Furthermore, the split out-of-round of the oval sleeve facilitates springing the sleeve into the casing in establishing the frictional engagements.

The frictional engagement, above referred to, can be accomplished by providing a sleeve, such as shown at 11', Figs. 6 and 7, with an inwardly extending elongated yieldable nib 33 which will engage the outer surface of the cartridge 12, thereby urging the sleeve 11 into frictional engagement with the casing 10, and also providing frictional engagement of the cartridge in the sleeve 11'. Aside from this modification, the sleeve 11' will be the same as the sleeve 11 and have an aperture 22' therein, the end stops 28', 27' and the split 23'.

With my improved construction, it will be apparent that, if the overall length of the lipstick is maintained, a much longer lipstick body 11 can be employed than is customary with other devices of this kind, this being due to the fact that the cartridge is movable throughout the full length of the casing, the casing having an aperture sufficiently long to permit of this movement, whereas the sleeve maintains a closure to the casing opening to minimize the area of the cartridge exposed therethrough. It will be understood that the cartridge is free to be rotated in the sleeve, while the sleeve is keyed against rotary movement in the casing.

Having fully described my invention what I claim as new and desire to secure by Letters Patent is:

1. A lipstick holder comprising an annular tubular body, one end of the body being open, a closure cap at the other end of said body, a cartridge mounted in and movable longitudinally of said body, means on the cartridge for supporting a lipstick in conjunction with one end thereof, a sleeve interposed between the cartridge and body, means within said body for keying the sleeve for sliding movement longitudinally of the body, said sleeve being confined within end limits of said body and cap in all positions thereof, the body and sleeve having registering elongated and circumferentially wide apertures, the aperture of the body being of greater length than the aperture of said sleeve, the cartridge being exposed through the aperture of said sleeve in all positions of the sleeve and cartridge in said body for accessibility through the aperture in said body, and means on said body and including said cap for limiting movement of the sleeve in both directions in said body.

2. A lipstick holder comprising an annular tubular body, one end of the body being open, a closure cap at the other end of said body, a cartridge mounted in and movable longitudinally of said body, means on the cartridge for supporting

a lipstick in conjunction with one end thereof, a sleeve interposed between the cartridge and body, means within said body for keying the sleeve for sliding movement longitudinally of the body, said sleeve being confined within end limits of said body and cap in all positions thereof, the body and sleeve having registering elongated and circumferentially wide apertures, the aperture of the body being of greater length than the aperture of said sleeve, the cartridge being exposed through the aperture of said sleeve in all positions of the sleeve and cartridge in said body for accessibility through the aperture in said body, means on said body and including said cap for limiting movement of the sleeve in both directions in said body, and said last named means comprising an inturned annular flange at the open end of said body.

3. A lipstick holder comprising an annular tubular body, one end of the body being open, a closure cap at the other end of said body, a cartridge mounted in and movable longitudinally of said body, means on the cartridge for supporting a lipstick in conjunction with one end thereof, a sleeve interposed between the cartridge and body, means within said body for keying the sleeve for sliding movement longitudinally of the body, said sleeve being confined within end limits of said body and cap in all positions thereof, the body and sleeve having registering elongated and circumferentially wide apertures, the aperture of the body being of greater length than the aperture of said sleeve, the cartridge being exposed through the aperture of said sleeve in all positions of the sleeve and cartridge in said body for accessibility through the aperture in said body, means on said body and including said cap for limiting movement of the sleeve in both directions in said body, and means at the ends of the sleeve for limiting movement of the cartridge in both directions therein.

4. A lipstick holder of the class described, comprising an elongated tubular body open at both ends, a cap for closing the lower end of said body, a sleeve slidably mounted in the body, the walls of the sleeve and body having circumferentially wide elongated openings, means for keying the sleeve in the body to maintain the openings in registered position, a lipstick supporting cartridge arranged in and movable longitudinally of said sleeve, means including said cap retaining the sleeve within end limits of said body, and means at the ends of said sleeve for checking movement of the cartridge in both directions in said sleeve.

5. A lipstick holder of the class described, comprising an elongated tubular body open at both ends, a cap for closing the lower end of said body, a sleeve slidably mounted in the body, the walls of the sleeve and body having circumferentially wide elongated openings, means for keying the sleeve in the body to maintain the openings in registered position, a lipstick supporting cartridge arranged in and movable longitudinally of said sleeve, means including said cap retaining the sleeve within end limits of said body, means at the ends of said sleeve for checking movement of the cartridge in both directions in said sleeve, said cartridge being rotatable in said sleeve, and said sleeve comprising a split tube providing tensioned frictional mounting of the sleeve in said body.

6. A lipstick holder of the class described, comprising an elongated tubular body open at both ends, a cap for closing the lower end of said body,

a sleeve slidably mounted in the body, the walls of the sleeve and body having circumferentially wide elongated openings, means for keying the sleeve in the body to maintain the openings in registered position, a lipstick supporting cartridge arranged in and movable longitudinally of said sleeve, means including said cap retaining the sleeve within end limits of said body, means at the ends of said sleeve for checking movement of the cartridge in both directions in said sleeve, said cartridge being rotatable in said sleeve, said sleeve comprising a split tube providing tensioned frictional mounting of the sleeve in said body, and means integral with the sleeve yieldably engag- 15 gaging said cartridge to frictionally hold the cartridge in said sleeve.

7. A lipstick holder of the class described comprising a tubular casing, a lipstick supporting cartridge slidably and rotatably mounted in said casing, the casing having an elongated circumferentially wide aperture in one wall thereof, the cartridge being exposed through the aperture in the casing in all positions of the cartridge in the casing to be accessible for manual movement, and means movably supported in the casing and re- 20 tained substantially within end limits of said casing for checking movement of the cartridge in the casing and for closing part of the aperture in the casing in different positions of the cartridge in said casing.

8. A lipstick holder of the class described comprising a tubular casing, a lipstick supporting cartridge slidably and rotatably mounted in said casing, the casing having an elongated circumferentially wide aperture in one wall thereof, the cartridge being exposed through the aperture in the casing in all positions of the cartridge in the casing to be accessible for manual movement, means movably supported in the casing and re- 25 tained substantially within end limits of said 40 casing

casing for checking movement of the cartridge in the casing and for closing part of the aperture in the casing in different positions of the cartridge in said casing, and means within circumferential boundaries of the casing for keying said means to control movement thereof in said casing.

9. A lipstick holder of the class described comprising a tubular casing, a lipstick supporting cartridge slidably and rotatably mounted in said casing, the casing having an elongated circumferentially wide aperture in one wall thereof, the cartridge being exposed through the aperture in the casing in all positions of the cartridge in the casing to be accessible for manual movement, means movably supported in the casing and retained substantially within end limits of said casing for checking movement of the cartridge in the casing and for closing part of the aperture in the casing in different positions of the cartridge in said casing, means within circumferential boundaries of the casing for keying said means to control movement thereof in said casing, and said first named means having means providing frictional support thereof in the casing.
